UNITED STATES PATENT OFFICE.

HATTIE BAVIER, OF NEW YORK, N. Y.

GARMENT-SUPPORTER.

SPECIFICATION forming part of Letters Patent No. 718,304, dated January 13, 1903.

Application filed June 23, 1902. Serial No. 112,729. (No model.)

To all whom it may concern:

Be it known that I, HATTIE BAVIER, a citizen of the United States, residing in New York, in the State of New York, have invented 5 certain new and useful Improvements in Garment-Supporters, of which the following is a specification.

This invention relates to improvements in dress-supporters for supporting the skirt at 10 the back of the same.

The object of the invention is to provide 15 means whereby the skirt is held up and the waist held down and at the same time a slight play between the parts permitted to accommodate for the ordinary slight movement of the skirt during use without the same becoming disengaged from the supporter.

The object is, further, to provide a supporter 20 which will permit of some latitude in the application of the same, so that the skirt-band may be applied more or less tightly, as may be desired.

The invention consists in the combination, 25 in a garment-supporter, of a back plate provided with means for securing the same to a suitable tape, projections of dovetail form connected at their inner narrower ends with said back plate at the upper edge of the same and projecting in upward direction there- 30 from, and safety-pin hooks provided with slots at their upper hook portions, said slots or openings being of approximately the same width as said dovetail projections at their widest part and said hooks being adapted to 35 interlock with said projections while engag- ing the main portion or body of said back plate, said dovetail projections thereby preventing accidental disengagement of said hooks from the plate.

40 In the accompanying drawings, Figure 1 is a perspective view of a shirt-waist as seen from the back. Fig. 2 is a perspective view of a garment-supporter employing my im- proved back plate in corresponding position. 45 Fig. 3 is a perspective view of a skirt also as seen from the back, and Fig. 4 is a detail ele- vation showing the back plate and safety-pin hooks as applied to a waist and skirt.

Similar letters of reference indicate corre- 50 sponding parts.

Referring to the drawings, A indicates the shirt-waist, and B the skirt.

a indicates the supporter belt or tape. This tape *a* is made of strong woven fabric or any other suitable material. It is provided at one 55 end with a suitable buckle *a'*. Upon the tape is located the back plate *b*, which may be made of brass, suitably nickel-plated, and which is provided with slots *b' b²*, one at each end, through which the tape *a* passes. At 60 its lower edge the main portion or body of the plate *b* is preferably made plain without projections; but at its upper edge it is pro- 65 vided with two projections *b⁴ b⁵*. These pro- jections are dovetail in form—*i. e.*, of larger width at their outer than at their inner ends or portions—and connected at their inner portions with the main portion or body of the back plate.

c c' c² are safety-pin hooks, composed each 70 of a safety-pin of the ordinary type, to the upper stationary bar or body of which is at- 75 tached the hook portion *c³*, which is provided at its upper part with a slot or opening for engaging upon the dovetail projections *b⁴ b⁵* of the plate. The lower hook *c* does not re- 80 quire to have an opening; but in order that the pins may be used interchangeably for either the waist or skirt all the hooks have openings.

The safety-pin hook *c* is first applied to the shirt-waist at about the middle of the back, at the lower portion a little above the waist- 85 line, with the hook portion of said safety-pin hook directed upwardly, as shown in Figs. 1 and 4. The other safety-pin hooks *c' c²* are applied to the inside of the skirt at the band, with the hook portion directed downwardly, 90 said safety-pin hooks being arranged one at each side of the placket-opening, as shown in Fig. 3. The tape, with the back plate upon it, is buckled about the wearer over the lower portion of the waist, the lower edge of the back plate being seated upon the hook *c*. The skirt is now applied and the safety-pin 95 hooks *c' c²* hooked over the dovetail projec- tions *b⁴ b⁵*, all in the manner indicated in Fig. 4.

As the projections *b⁴ b⁵* are made at their inner ends or portions of less width than the 100 slots in the safety-pin hooks, they permit a slight movement of the hooks along the upper edge of the main portion of the plate, so as to lessen the strain on the garment in the

ordinary movements during use, while at the same time, as before referred to, preventing accidental release of the hooks from the plate.

Instead of placing the safety-pin hooks over the projections, as indicated in full lines in Fig. 4, the same may be placed at the inside of the dovetail projections, as indicated in dotted lines, thereby drawing the band of the skirt tighter. This is a valuable feature, as it permits the adjustment of the skirt and obviates the necessity of accuracy in applying the safety-pin hooks to the skirt.

Having thus described my invention, I claim as new and desire to secure by Letters 15 Patent—

1. In a garment-supporter, the combination, with a back plate consisting of a body portion provided with means for securing the same upon a suitable tape, and dovetail projections connected at their inner narrower ends or portions with said plate at its upper edge and extending in upward direction therefrom, of safety-pin hooks adapted to engage the main portion or body of said plate, and 20 said dovetail projections of the plate being adapted to engage at their sides with said

hooks for preventing accidental disengagement of the latter from said main portion or body of the plate, substantially as set forth.

2. In a garment-supporter, the combination of a back plate, comprising a body portion provided with means for securing the same upon a suitable tape, dovetail projections connected at their inner narrower portions with the body portion of the plate at the upper edge of the same and extending in upward direction therefrom, and safety-pin hooks provided each in its upper or hook portion with an opening of approximately the same width as said projections at their wider portion, said dovetail projections being adapted to engage at their sides with said hooks for preventing accidental disengagement of the latter from the main portion or body of the plate, substantially as set forth. 35

In testimony that I claim the foregoing as my invention I have signed my name in presence of two subscribing witnesses.

HATTIE BAVIER. 40
